ALKYLTHIOMETHYL PHOSPHONIUM DERIVATIVES

Donald J. Peterson, Cincinnati, Ohio, assignor to The Procter & Gamble Company, Cincinnati, Ohio
No Drawing. Original application Mar. 13, 1967, Ser. No. 622,419, now Patent No. 3,502,731, dated Mar. 24, 1970. Divided and this application Jan. 19, 1970, Ser. No. 4,042.

Int. Cl. C07f 9/54; D06m 13/28

U.S. Cl. 260—606.5 F

6 Claims

10 dodecatrienyl, allyl, 3-dodecanyl, 8-tetradecenyl, 2-dodecanyl, 2,4-hexadienyl, 2,4-dodecadienyl, isopropyl, butyl, 2-butanyl, hexyl, octyl, decyl, tetrapropylene, dodecyl, tridecyl, tetradecyl, pentadecyl, hexadecyl, octadecyl, eicosyl, and 2-octadecenyl groups.

15 R^6 can also be an aralkyl group (benzyl, 12-phenyldodecyl, 1-naphthylmethyl, 2-biphenyl-2-ethyl, etc.). Suitable substituted R^6 groups include 4-methoxybenzyl, 3,6,9,12 - tetraoxaoctadecyl, and 3 - diethylaminopropyl groups.

20 The hydroxy sulfides can be oxidized to the corresponding sulfoxides and/or sulfones or they can be reacted with an excess of the conventional organic halides and pseudo halides to give the corresponding sulfonium salts. Many 15 of these compounds are known. As with the corresponding dialkyl sulfoxides, the hydroxyalkyl and alkoxyalkyl sulfoxides and sulfones are detergents when they contain one long alkyl chain of from 8 to 20 carbon atoms and the sulfoxides and sulfones are fabric softeners for cotton when they 20 contain two long alkyl chains. Hydroxy and alkoxy sulfides containing less than about 8 carbon atoms are excellent solvents for, e.g., glycerides. Sulfonium salts containing two long alkyl chains are substantive fabric softeners for cotton when applied from dilute solutions.

REACTION WITH ALKYL OR ARYL, HALO AND PSEUDO HALO PHOSPHINES

25 Alkylthiomethylmetal compounds react readily with trihalophosphines, haloalkylphosphines, and haloarylphosphines according to the following equation:

30 35 wherein each R^9 in the above equation is an alkyl, aryl, aralkyl, or alkaryl group containing 1 to 30 carbon atoms, 1 to 10 oxygen atoms as substituents replacing methylene groups in alkyl and alkylene groups, and 0 to 5 substituent tertiary amino groups wherein X^3 is either a halogen atom, either chlorine, bromine, or iodine or a pseudo 40 halogen group such as $R''O^-$, $-NR_2^-$ and $-SO_4R''$, wherein R'' is selected from the group consisting of alkyl, aryl, alkaryl and aralkyl groups containing from 1 to 30 carbon atoms, from 0 to 10 substituent oxygen atoms 45 replacing methylene groups in alkyl and alkylene groups and from 0 to 5 substituent tertiary amino groups, M is an alkali metal, e.g. sodium, potassium or lithium and wherein n is either 0, 1 or 2. These compounds will undergo several reactions. For example, the compounds can be 50 55 oxidized step-wise as described hereinbefore to the following compounds.

60 65 R^9 in the above formulas and equations is preferably either a phenyl group or an alkyl chain containing from 1 to 20 carbon atoms. Examples of these groups are: methyl, ethyl, propyl, 2,4-hexadienyl, 2,4-dodecadienyl, 2,7-tetradecadienyl, 2,4,6-dodecatrienyl, allyl, 3-dodecanyl, 8-tetradecenyl, 2-dodecanyl, 2,4-hexadienyl, 2,4-dodecadienyl, isopropyl, butyl, 2-butanyl, hexyl, octyl, decyl, tetrapropylene, dodecyl, tridecyl, tetradecyl, hexadecyl, octadecyl, eicosyl, and 2-octadecenyl groups.

70 R^9 can be an aryl group (e.g., phenyl, biphenyl, or naphthyl groups); an alkaryl group (4-decylphenyl, 4-methyl-1-naphthyl, ethyldiphenyl, 2-methylphenyl, etc.);

SUMMARY

This invention relates primarily to the discovery that it is possible to prepare alkylthiomethyl phosphonium compounds by reacting organic halides or pseudo halides with alkylthiomethylphosphines depictable by the formula $R-S-CH_2$ -phosphine.

Wherein R is a saturated alkyl group containing from 1 to 30 carbon atoms, from 0 to 10 substituent oxygen atoms replacing methylene groups in alkyl and alkylene groups, and from 0 to 2 substituents selected from the group consisting of aryl groups, alkaryl groups, and tertiary amino groups, said substituents being placed so that no aryl moiety, oxygen atom, or nitrogen atom is attached to any carbon atom which is less than three atoms removed from the sulfur atom.

CONVENTIONAL ORGANIC HALIDES AND PSEUDO HALIDES

R^6 is preferably an alkyl group, either saturated or unsaturated, containing from one to 20 carbon atoms. Examples of these groups are: methyl, ethyl, propyl, 2,4-hexadienyl, 2,4-dodecadienyl, 2,7-tetradecadienyl, 2,4,6-dodecatrienyl, allyl, 3-dodecanyl, 8-tetradecenyl, 2-dodecanyl, 2,4-hexadienyl, 2,4-dodecadienyl, isopropyl, butyl, 2-butanyl, hexyl, octyl, decyl, tetrapropylene, dodecyl, tridecyl, tetradecyl, hexadecyl, octadecyl, eicosyl, and 2-octadecenyl groups.

3

or an aralkyl group [benzyl, 12-phenyldodecyl, 1-naphthylmethyl, 2-(4-biphenyl)-ethyl, etc.] These groups are also preferred. Suitable substituted R⁹ groups include 4-methoxyphenyl, 3,6,9,12 - tetraoxaoctadecyl, 3,6 - di-dimethylamino)hexyl, and 3-diethylaminopropyl groups.

The preferred X³ is chlorine.

The products of the reactions of alkylthiomethylmetal compounds with the phosphites and halophosphines and the oxidized and/or sulfurized analogs of said products have the generic formula:

wherein y is 0 or 1, Q is ($\rightarrow O$) or ($\rightarrow S$), each z is 0, 1 or 2, when Q is ($\rightarrow O$), 0 or 1 when Q is ($\rightarrow S$) and 0 when y is 0, L is an integer from one to three, and R and R⁹ have the definitions given hereinbefore.

The compounds which contain phosphine oxide moieties are surface active agents useful for forming oil in water emulsions when one of the R groups contains about 8 to about 24 carbon atoms and the other R groups are short alkyl groups. All of these compounds have herbicidal characteristics and are lubricant additives as discussed hereinbefore. When there are two long alkyl groups of from 12 to 24 carbon atoms in these compounds they are textile softeners for cotton when used at a level of about 1% by weight of the cloth and applied in a padding bath.

All of the above compounds which contain sulfide groups and phosphine groups can be converted to phosphonium compounds with a conventional organic halide or pseudo halide R⁶X² as hereinbefore described according to the following equation:

When the phosphonium compounds contain one long alkyl chain of from about 8 to about 14 carbon atoms they are effective surface active agents. When the compounds contain two long alkyl chains of from 16 to about 24 carbon atoms these compounds are substantive textile softeners.

The phosphonium compounds can be reacted with, e.g., sodium hydroxide according to the disclosure in the co-pending application of Hays, Ser. No. 329,281, filed Dec. 9, 1963, to form the phosphine oxide compounds described hereinbefore which contain sulfide groups.

All parts, percentages and ratios herein are by weight unless otherwise specified. The following examples are illustrative of the invention and should not be taken as limiting the scope of the claims.

EXAMPLE I

Preparation of methylthiomethylolithium

5.8 gm. (0.05 mole) of N,N,N',N'-tetramethylethlenediamine (TMEDA) was added to 36 ml. of 1.4 molar (0.05) n-butyllithium in hexane to form 0.05 mole of the n-butyllithium-TMEDA complex. (The temperature in these reactions was held below about 20° C. by means of a water bath.) 3.1 g. (0.05 mole) of dimethyl sulfide was added to the complex and after about a quarter of an hour a white precipitate had formed. This precipitate was composed of lithium methyl mercaptide and methylthiomethylolithium. After about four hours, the resulting reaction mixture containing the methylthiomethylolithium (MTML) was used in the following reactions. All reactions herein (including Examples II-XVI) were carried out in an inert atmosphere of nitrogen.

When in the above example the following alkyl methyl sulfides are substituted on a molar basis for the dimethyl sulfide, substantially equivalent results are obtained in that the corresponding alkylthiomethylolithium compounds are prepared: methyl, ethyl, n-propyl, isopropyl, n-pentyl, isopentyl, n-hexyl, 2,2-dimethylpentyl, n-heptyl, n-octyl, 2,2-dimethylhexyl, isooctyl, 2-ethylhexyl, n-nonyl, n-decyl,

4

tripropylene, undecyl, n-dodecyl, tetrapropylene, tridecyl, n-tetradecyl, pentadecyl, n-hexadecyl, n-octadecyl, eicosyl, cyclopentyl, cyclohexyl, cyclohexylmethyl, methylcyclohexyl, 2-cyclohexylidodecyl, 12-cyclohexylidodecyl, 4-dodecylcyclohexyl, cyclooctyl, phenyl, biphenyl, naphthyl, 3-phenyldodecyl, 4-methyldecyl, 4-phenyloctyl, 4-decyl, 4-phenylbutyl, 3-methyldecyl, 3-(1-naphthyl)propyl, 4-(1-naphthyl)butyl, 3-ethyl-3-(4-biphenyl)propyl, and 3-(4-biphenyl)propyl methyl sulfides.

10 When in the above example the following metalating agents are substituted on a molar basis for n-butyllithium-TMEDA complex substantially equivalent results are obtained in that the alkylthiomethylmetal compounds are prepared: phenylsodium; phenylpotassium; methyl, ethyl, propyl, butyl, pentyl, octyl, decyl, tetrapropylene, hexadecyl, dodecyl, octadecyl, and eicosyl sodiums and potassiums; the complexes of methyl, ethyl, propyl, butyl, pentyl, octyl, decyl, tetrapropylene, hexadecyl, dodecyl, octadecyl and eicosyl lithiums with N-methyl, N-ethyl, N'-propyl, N'-butylpropylenediamine, N-dodecyl, N,N,N'-trimethylmethylenediamine, N-octyl, N,N,N'-triethylbutylenediamine, N,N,N',N'-tetraethylpropylenediamine, or N-eicosyl, N,N,N',N'-trimethylethylenediamine or t-butyllithium with diazabicyclo(2.2.2.)octane.

When in the above example the following saturated hydrocarbons are substituted, either wholly or in part (e.g., 1:1 mixtures), for the hexane, substantially equivalent results are obtained in that the alkylthiomethylmetal compounds are prepared: pentane, octane, isoctane, nonane, decane, isododecane, and cyclohexane.

EXAMPLE II

Reaction of chlorodiphenylphosphine with methylthiomethylolithium

35 0.2 mole of the filtrate of Example I was added dropwise over a period of one hour to a solution of 44 g. (0.2 mole) of chlorodiphenylphosphine in 100 ml. of tetrahydrofuran. The mixture was stirred for an additional 40 two hours and the reaction mixture was carefully hydrolyzed with 100 ml. of 2.5 molar ammonium chloride. The organic layer was dried, concentrated and distilled under reduced pressure to give 24.4 g. of (methylthiomethyl)diphenylphosphine, B.P. 160-165° C. (0.5 mm.). The product gave rise to a P³¹ NMR signal at +21 p.p.m. in CHCl₃ and H¹ NMR signals centered at τ 2.8 (aromatic), 7.08 (methylene, doublet, J=3 cps.), and 8.02 (methyl, singlet) in the correct area ratios.

45 When in the above example the following halo, halo alkyl or aryl phosphines are substituted on a molar basis for the chlorodiphenylphosphine, substantially equivalent results are obtained in that the corresponding (methylthiomethyl)alkyl or aryl phosphines are prepared:

50 phosphorus trichloride, phenylmethylchlorophosphine, 55 diallylchlorophosphine, dimethylchlorophosphine, dodecylmethylchlorophosphine, dimethyliodophosphine, dodecylidichlorophosphine, hexadecylbromophosphine, (2-octadecynyl)-1-naphthylchlorophosphine, 60 4-biphenylisopropylchlorophosphine, 3,6,9,12-tetraoxaoctadecylmethylbromophosphine, 4-methoxyphenylchlorophosphine, and (3-diethylaminopropyl)phenylchlorophosphine.

65 When in the above example any of the alkylthiomethyl alkali metals of Example I are substituted for the methylthiomethylolithium a molar basis, substantially equivalent results are obtained in that the corresponding (alkylthiomethyl)alkyl or aryl phosphines are prepared.

70 These products are all useful as lubricant additives, herbicides, and intermediates in the preparation of other compounds as described in detail both hereinbefore and hereinafter.

EXAMPLE III

Quaternization of (methylthiomethyl)diphenylphosphine

Treatment of 1.5 ml. of the (methylthiomethyl)diphenylphosphine with an excess of methyl iodide in 20 ml. of acetone gave 2.45 g. of diphenylmethyl(methylthiomethyl)phosphonium iodide, M.P. 161.5-163.5° C. The NMR analysis in $CDCl_3$ was: H^1 signals centered at τ 2.18 (aromatic), 5.27 (methylene, doublet, $J=8$ cps.), 7.07 ($\equiv PCH_3$, doublet, $J=13$ cps.), and 7.71 ($—SCH_3$, singlet).

When in the above reaction any of the other phosphine reaction products of Example II are substituted on a molar basis for the (methylthiomethyl)diphenylphosphine, substantially equivalent results are obtained in that the corresponding phosphonium iodides are prepared.

When in the above reaction the following halides and pseudo halides are substituted on a molar basis for the methyl iodide, substantially equivalent results are obtained in that the corresponding phosphonium salts are prepared: ethyl; allyl; isopropyl; tetrapropylene; dodecyl; 2-dodecynyl; 2,4-dodecadiynyl; 2,4-dodecadienyl; benzyl; 1-naphthylmethyl; (2-biphenyl)-2-ethyl; 4-methoxybenzyl; 3,6,9,12-tetraoxaoctyl; and 3-diethylaminopropyl chlorides, bromides, iodides and methyl sulfates.

EXAMPLE IV

When in the previous Example II, the following solvents are substituted, either wholly or in part (e.g., 1:1 mixture), for the tetrahydrofuran, substantially equivalent results are obtained in that the reaction proceeds without interference: pentane; hexane; octane; icoctane; nonane; decane; isododecane; cyclohexane; diethyl ether; dibutyl ether; diphenyl ether; 1,2-dimethoxyethane; and diethylene glycol dimethyl ether.

EXAMPLE V

When in the previous Example II, any of the alkylthiomethylmetal compounds of Example I are substituted for the methylthiomethyl lithium or n-decylthiomethyl lithium compounds, substantially equivalent results are obtained in that analogous compounds are prepared.

EXAMPLE VI

The detergent compounds of this invention can be used to formulate detergent compositions having the following formulas:

	Percent
Detergent compounds of this application	17.5
Sodium sulfate	23
Sodium tripolyphosphate	50
Sodium silicate	6
Water	3.5
Granular detergent	
Detergent compounds of this application	10
Sodium dodecylbenzenesulfonate (the dodecyl group being derived from tetrapropylene)	10
Sodium nitrilo triacetate	50
Sodium sulfate	30
Granular detergent	
Detergent compounds of this application	10
Condensation product of one mole of nonyl phenol and nine moles of ethylene oxide	10
Sodium pyrophosphate	50
Sodium carbonate	3
Trisodium phosphate	3
Sodium sulfate	24
Milled toilet bar	
Detergent compounds of this application	10
Sodium coconut oil soap	15
Sodium tallow soap	65
Moisture	75

Milled toilet bar

5	Detergent compounds of this application	50
	Tallow fatty acid	25
	Moisture	15
	Constarch	5
	Triethanolammonium ethylenediaminetetraacetate	5
Scouring cleanser		
10	Silica flour	85
	Detergent consisting of 85% trisodium phosphate and 15% of the detergent compounds of this application	15
Liquid detergent		
15	Sodium dodecyl benzene sulfonate	6
	Detergent compounds of this application	6
	Potassium pyrophosphate	20
	Potassium toluene sulfonate	8
20	Sodium silicate	3.8
	Carboxymethyl hydroxyethyl cellulose	0.3
	Water	Balance
Liquid detergent		
25	Detergent compounds of this application	10
	Tetrasodium ethylenediaminetetraacetate	25
	Water	65
Examples of detergent compounds of this application include sodium, potassium, and ammonium decyl, dodecyl, and tetradecyl thioacetates; dodecylbis(methylthioethyl)phosphine oxide; octadecyl(ethylsulfonylmethyl)methylphosphine oxide; (tetradecylthiomethyl)dimethylphosphine oxide; and (octadecylsulfonylmethyl)diethylphosphine oxide. Other detergents disclosed herein and especially in Example III, can be substituted for the above examples to give substantially equivalent results in that the compositions have detergent properties. These detergent compositions are used according to the teachings of the prior art with respect to similar detergent compositions.		
30		
35		
40		
	What is claimed is:	
	1. Compounds having the formula:	
45	$(RSCH_2)_L P^{\oplus} (R^6)_3-L R^6 X^2 \ominus$	
	wherein R is a saturated alkyl group containing from 1 to 30 carbon atoms, from 0 to 10 substituent oxygen atoms replacing methylene groups in alkyl and alkylenegroups to form ether linkages, there being at least two carbon atoms separating each oxygen atom from any other oxygen atom, from 0 to 2 substituents selected from the group consisting of phenyl, naphthyl and biphenyl groups, said substituents being placed so that no aryl moiety or oxygen atom is attached to any carbon atom which is less than three atoms removed from the sulfur atom, wherein L is an integer from 1 to 3, wherein R^6 is selected from the group consisting of alkyl and aralkyl groups containing from 1 to 30 carbon atoms and from 0 to 10 substituent oxygen atoms replacing methylene groups in alkyl and alkylenegroups to form ether linkages, there being at least two carbon atoms separating each oxygen atom from any other oxygen atom, wherein X^2 is selected from the group consisting of chlorine, bromine, and iodine atoms and wherein each R^6 is selected from the group consisting of alkyl, aryl, aralkyl, and alkaryl groups containing from 1 to 30 carbon atoms, 1 to 10 oxygen atoms as substituents replacing methylene groups in alkyl and alkylenegroups to form ether linkages, there being at least two carbon atoms separating each oxygen atom from any other oxygen atom.	
	2. The compounds of claim 1 wherein L is 2 or 3.	
	3. The compounds of Claim 1 wherein R^6 contains from about 8 to about 14 carbon atoms.	

4. The compounds of claim 1 wherein L is 1 and R⁹ contains from about 16 to about 24 carbon atoms.

5. The compounds of claim 1 wherein R is methyl, R⁹ is phenyl, R⁶ is methyl and L is 1.

6. The compounds of claim 2 wherein R is methyl, R⁹ is phenyl, and R⁶ is methyl.
